CLAIM

I claim the ornamental design for an air bed, as shown and described.

DESCRIPTION

FIG. 1 is a front, right and top side perspective view of an air bed showing our new, original, and ornamental design; FIG. 2 is a rear, left and bottom side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of the area indicated by circle "9" in FIG. 1;

FIG. 10 is an enlarged detail view of the area indicated by circle "10" in FIG. 3; and,

FIG. 11 is an enlarged detail view of the area indicated by circle "11" in FIG. 5.

The dashed lines illustrate features of the air bed that form no part of the claimed design. The dot-dash broken lines encircling portions of the air bed in FIGS. 1, 3 and 5 indicate details shown as enlarged views in FIGS. 9, 10 and 11. The dot-dash lines in FIGS. 9, 10 and 11 show the boundaries of the detail views and form no part of the claimed design.
